UNITED STATES PATENT OFFICE.

BERTRAND S. SUMMERS, OF PORT HURON, MICHIGAN.

BLEACHING AND WASHING COMPOSITION.

No Drawing.

Application filed December 17, 1921. Serial No. 523,170.

To all whom it may concern:

Be it known that I, BERTRAND S. SUMMERS, a citizen of the United States, residing at Port Huron, county of St. Clair, ⁵ State of Michigan, have invented certain new and useful Improvements in Bleaching and Washing Compositions, of which the following is a specification.

My invention relates to a bleaching powder containing as its main ingredient calcium hypochlorite. Ordinarily such bleaching powder is made by passing chlorine through lime and thereby converting a considerable portion thereof into calcium hypochlorite, a considerable quantity of the lime, however, remaining in the unconverted state. This material is used for a great variety of purposes, such as for whitening goods and for cleaning purposes and owes ¹⁰ its effectiveness to the oxidizing action of the oxygen evolved by a combination of a portion of the chlorine of the bleaching powder with the hydrogen of water. This material has been put upon the market in ¹⁵ the form of a dry powder and when freshly made is very efficient for the purposes for which it is used. As ordinarily made, however, it rather rapidly loses its effectiveness, becoming largely converted into calcium ²⁰ chloride with the evolution of oxygen. In order to so far as possible preserve the material in its full strength it is commonly enclosed in moisture excluding packages, but even with this precaution it becomes weak ²⁵ and ineffective after the lapse of a comparatively short period.

It is the purpose of my invention to enhance the bleaching effect of bleaching powder and also to so preserve it that it may ³⁰ be kept a considerable time without appreciable loss of strength. It is a further purpose of the invention to avoid any deleterious effect of the released chlorine upon the material treated with the bleaching ³⁵ powder. I have discovered that if the bleaching powder is mixed with sodium bicarbonate a much more intense bleaching effect is obtained and that if the bicarbonate is mixed dry with the freshly formed

bleaching powder the disagreeable odor of ⁵⁰ the latter is largely removed, the compound will keep well without unduly losing strength and when the mixture is dissolved in water a reaction takes place in which the calcium of the bleaching powder is precipitated in the form of carbonate. If the bicarbonate is added to a solution of the bleaching powder a double decomposition ⁵⁵ takes place, the reaction proceeding so energetically as to cause considerable effervescence, due to the evolution of chlorine and oxygen and thus a considerable portion of these gases is lost without doing the intended work. When, however, the bleaching powder and bicarbonate are mixed dry and subsequently dissolved in water the reaction takes place very much more slowly ⁶⁰ with the result that the chlorine and oxygen enter fully into the bleaching action and consequently the effect is greatly enhanced. ⁶⁵ Preferably the bicarbonate is added in smaller quantity than is required to combine with all of the calcium of the hypochlorite.

In preparing the commercial article I add ⁷⁰ about three parts of fresh bleaching powder, which may be prepared in the usual manner, to about one part of sodium bicarbonate, thoroughly mixing these materials and reducing any lumps therein to powder. The ⁷⁵ mixture is preferably shipped and stored in closed receptacles such as those commonly employed for bleaching powder, though as my composition retains its strength better than ordinary bleaching powder, this is not ⁸⁰ essential.

Where I have used the term bleaching powder or calcium hypochlorite, I wish to be understood as referring to a compound ⁸⁵ containing calcium hypochlorite ($CaCl_2O$) such as is commonly found on the market under the name of bleaching powder. By the term sodium bicarbonate I mean to refer to sodium acid carbonate ($NaHCO_3$) or sodium hydrogen carbonate, commonly known ⁹⁰ as baking soda.

Where the composition is dissolved in water in considerable concentration as

where a powerful bleaching effect is desired, the calcium carbonate which forms may be allowed to settle, and the supernatant liquor decanted off and used for 5 the purpose. When the material is used in greater dilution no settling is required. In case the compound is used for scrubbing or the like the insoluble carbonate of lime formed is readily washed away.

I claim:

1. As an article of manufacture, a mixture of dry bicarbonate of an alkali metal and calcium hypochlorite.
2. As an article of manufacture, a mixture of dry sodium bicarbonate and calcium hypochlorite.

10

BERTRAND S. SUMMERS.
